UNITED STATES PATENT OFFICE

91,478

DESIGN FOR A COMBINED PHONOGRAPH HOOD AND SUPPORTING BASE THERE- FOR

Leland Stanford Briggs, Douglaston, N. Y., as-
signor to Dictaphone Corporation, New York,
N. Y., a corporation of New York

Application October 3, 1933. Serial No. 49,397

Term of patent 14 years

To all whom it may concern:

Be it known that I, LELAND STANFORD BRIGGS, a citizen of the United States, resident at Virginia Road, in the town of Douglaston, county of Queens, and State of New York, have invented a new, original, and ornamental Design for a Combined Phonograph Hood and Supporting Base Therefor, of which the following is a specification, reference being had to the accompanying drawing, forming part thereof, it being un-

derstood that the supporting base is not a material part of the design.

The figure is a perspective view of a combined phonograph hood and supporting base showing my new design.

I claim:

The ornamental design for a combined phonograph hood and supporting base therefor substantially as shown and described.

LELAND STANFORD BRIGGS.
